UNITED STATES PATENT OFFICE.

WILLIAM M. SMITH, OF WEST MERIDEN, CONNECTICUT, ASSIGNOR TO THE MERIDEN BRITTANIA COMPANY, OF SAME PLACE.

DESIGN FOR SOCKET FOR LIFTING-HANDLE.

Specification forming part of Design No. 5,319, dated October 17, 1871.

To all whom it may concern:

Be it known that I, WILLIAM M. SMITH, of West Meriden, in the county of New Haven and State of Connecticut, have invented a new Design for Socket for Lifting-Handle; and I do hereby declare the following, when taken in connection with the accompanying drawing and the letters of reference marked thereon, to be a full, clear and exact description of the same, and which said drawing constitutes part of this specification and represents a front view.

This invention relates to a design for the base of the socket for lifting-handles, such as are commonly called coffin-handles; and consists in the peculiar configuration of the base, as shown in the accompanying illustration and as herein-after described.

The general outline is of a rectangular form with a projection, *a*, upon each corner, enlarging the plate at the angles, as fully shown in the accompanying illustration. Other projections or ornaments, as at *d*, may be added upon the sides between the said projections; but my design is limited to the rectangular figure with projecting corners and with or without the intermediate ornamentation.

I claim as my invention—

The design for socket for lifting-handle, as herein described and shown in the accompanying illustration.

WILLIAM M. SMITH.
